UNITED STATES PATENT OFFICE.

HENRY C. OSBORN, OF CLEVELAND, OHIO, ASSIGNEE TO THE AMERICAN MULTIGRAPH COMPANY, OF CLEVELAND, OHIO, A CORPORATION OF OHIO.

MECHANISM FOR HOLDING TYPE LINES.

Application filed April 14, 1922. Serial No. 552,484.

To all whom it may concern:

Be it known that I, HENRY C. OSBORN, a citizen of the United States, residing at Cleveland, in the county of Cuyahoga and State of Ohio, have invented a certain new and useful Improvement in Mechanism for Holding Type Lines, of which the following is a full, clear, and exact description, reference being had to the accompanying drawings.

This invention relates to mechanism for holding lines of type. The general object of the invention is to provide a type holding member so arranged that when type having a short base are secured therein the combined height of the type and the holder will constitute the same height-to-paper as ordinary type.

It is frequently desirable to use cast line slugs, or individual type which are type high, in conjunction with type having short bases, such as the well known multigraph type. When this latter character of type is so used it becomes necessary to provide suitable means whereby the printing surface will be brought to a level with the printing surface of the type high type, and to accomplish this result is one of the objects of my invention.

It is a further object of my invention to provide a removable holder for a line of short individual type so constructed that the line may be treated as a unit and may be held on a type bed in printing position, so that such short type can be used in conjunction with type slugs or individual type of the usual height.

Another object of the invention is to provide means whereby printing slugs may be used on a cylindrical printing drum having type rails, such as a multigraph, and wherein short type, such as the usual multigraph type, may be used in conjunction with the printing slugs, the short type being provided with an auxiliary base whereby their height-to-paper is the same as that of the printing slug.

A still further object of the invention is to provide a cylindrical printing drum having a circumferentially grooved type receiving chase so arranged as to receive printing slugs and other printing characters adjacent the type carried by the rails mentioned. The chase, according to my invention has its type holding grooves disposed above the sur-

face of the drum, while the printing slugs and the type holders rest directly on the drum, thus making the printing surface of the type carried in the chase and also the characters on the slugs of the same height-to-paper.

Further and other objects of the invention will be apparent from the following description taken in connection with the accompanying drawings wherein Fig. 1 is an end elevation of a printing drum equipped with type holders constructed according to my invention; Fig. 2 is an enlarged fragmentary elevation of a printing drum showing my invention; Fig. 3 is a longitudinal section of a printing drum showing my type holders applied thereto, means for holding the type lines being shown in elevation; Fig. 4 is a perspective view of my type holder; and Fig. 5 is a fragmentary view similar to Fig. 3 showing a modified means for holding the type holding and printing drum.

Referring to the drawings by reference characters, I have shown at 10 a suitable type bed indicated as a drum which may be mounted to rotate in any desired manner. Mounted upon the type bed 10 I show a curved chase 12 which is indicated as fitting directly upon the drum. The upper surface of the chase 12 may be provided with rails 14 or other means for the purpose of receiving grooved type or cast slugs 16. The chase 12 may be provided with end flanges and may have lugs 17 on its under surface for receiving a securing element to be presently described.

Adjacent the end of the chase, I show a plurality of cast aligned slugs 20. These slugs may, however, be omitted if desired. Arranged adjacent these aligned slugs I show a plurality of type holding members 25. Each type holding member 25 is indicated as comprising a base portion 26 and a pair of diverging side members 27. The relation of the base 26 and the sides 27 is such that they form an approximate U. The members 25 are preferably made of sheet metal and hence are resilient.

The ends of the side members are indicated as provided with type engaging portions shown as inturned flanges forming shoulders 28. My holder is particularly adapt'd for use with grooved type 30, which type may comprise a number of individual type or a cast line of grooved type. The

sides 27 of the type holder, if intended for mounting on a drum, diverge and are preferably arranged so that each side of the holder lies in a radial plane which passes through 5 the axis of the drum. This arrangement allows the type holders to have a complete face to face engagement and lessens the liability of the members being inaccurately assembled, thus avoiding irregularities in the 10 printing. The holders 25 are preferably so formed that until the holder is mounted the shoulders 28 do not engage the neck 31 on the type but allow the latter to move freely above the shoulders, but when mounted they 15 may spring inwardly sufficiently to bind the type at the neck; or, if desired, the type heads may sufficiently overhang the holders so that the heads come into abutting engagement.

20 In order to secure the chase, the slugs and the type holders in position, I may provide suitable anchoring means here shown as members 34 and 35. The member 34 is preferably fixed in position while the member 25 35 is slidably mounted on the drum by reason of slotted portions 36 which receive screws 37. To provide adjustment a number of holes 38 may be provided for the screw 37.

In the preferred form of my invention, the 30 holder 25 is provided with slots 40 and the end portions of the slots are turned, as at 41, to provide a shoulder which extends substantially parallel with the flanges 28 on the type holder. The slugs 20 have apertures 35 therethrough similar to the apertures 40 and 41 in the holder 25. A fastening member, shown as a rod 42, is secured to the anchors 34 and 35. This rod is indicated as extending through the lugs 17 on the chase, through 40 the apertures in the slugs 20 and through the notches in the type holding members 25. The fastening rod may be provided with suitable tightening means, such as a nut 44, at one or both its ends.

45 As an alternate method of securing type holders in place, I may cut away the lower portion of the ends of the type holders, as as 50, and may form a notch 51 above the cut away portion. A suitable fastening member 50 52 which may be a segmented metallic band, may serve to hold the printing member in position. The band 52 may be slotted, as at 53, to receive a fastening member 54, which engages the drum.

55 In using machines which are adapted primarily to print from grooved type, it frequently is desirable to use in the same machine printing slugs which are type high and by constructing a chase, such as I have 60 shown, the printing surface of the type carried by the rails may be made to be at the same height as slugs whereby a uniform impression is secured. Furthermore, the height of the type carried in the holder is 65 the same as the height of the printing slugs

so that this type holder aligns with the slugs to give the proper impression.

By using my improved holder, I am enabled to use grooved type in conjunction with slugs, electrotypes, etc., which are type 70 high. I contemplate using my holder on curved or plane printing beds, although when the bed is plane, it is well to make the sides 27 of the holder parallel.

Having thus described my invention, I 75 claim:

1. In combination with a printing drum, a type holding member thereon, said type holding member comprising a sheet metal strip bent to form a base portion and two 80 side portions arranged substantially U-shaped, the sides of the U being disposed in radial planes passing through the center of the drum.

2. A resilient U-shaped type holder 85 adapted to be compressed to lock a line of type therein and having a longitudinally extending shoulder thereon, and an arcuate holding member adapted to engage said shoulder by relative movement of one with 90 respect to the other.

3. The combination with a rotary drum, of resilient sheet metal type holding members arranged thereon side by side, each type holding member comprising a substantially 95 U-shaped portion having a base and a pair of diverging side walls, said side walls lying substantially in radial planes which converge at a point.

4. The combination with a printing drum, 100 of a one piece sheet metal resilient type holding member thereon, said type holding member being U-shaped, the sides of the U being arranged in radial planes passing 105 through the center of the drum, and a retaining member extending through the holder above the base of the U.

5. In combination, a printing drum having type rails mounted in a chase thereon, type on said rails, type holding members having type therein, all said type being arranged at the same height, and means engaging said chase, and said holding member for securing them on said drum. 110

6. In a printing device, a drum, resilient sheet metal type holding members arranged thereon side by side, each type holding member comprising a substantially U-shaped portion having a base and a pair of diverging 115 side walls, the inner end of said side walls having means thereon for engaging type, type in said holder normally free to slide therein but adapted to be gripped by the engaging means.

7. A type holder comprising a U-shaped member having a type receiving groove therein and having a notch intersecting the base of the U and extending some distance along the sides thereof, the end of said slot 120 being laterally deflected to provide a direc- 125

tion substantially parallel to said type receiving groove.

8. The combination with a support of a type holding member and a plurality of type having grooves in their sides, said type holding member being substantially U-shaped and having type engaging means thereon, and means passing through said member beneath said type for holding said members in position on said support.

9. A type holder having a type receiving groove therein, type in said groove, said holder having an overhanging notch therein, said notch being arranged beneath the type, a rod-like holding member adapted to have relative longitudinal movement with respect to the typeholder to engage the shoulder provided by the notch, and means for tightening said holding member.

10. The combination of a type holding member and a plurality of type having grooves in their sides, said type holding member being made of sheet metal bent into a substantially U-shape and having inwardly directed flanges at its type engaging end, and means arranged beneath said type for holding said member in position, said means comprising a rod occupying an L-shaped notch leading from the bottom of the holder and forming a shoulder.

11. A type holder comprising a U-shaped member having a type receiving groove therein and having a notch intersecting the base of the U and extending some distance along the sides thereof, the end of said notch being laterally deflected to provide a shoulder extending in a direction of the type receiving groove, and means on said holder for engaging type.

12. The combination of a rotary printing member, a type holder secured thereon,

said type holder comprising a U-shaped member having a type receiving groove therein and having a notch intersecting the base of the U and extending some distance along the sides thereof, the end of said notch being laterally deflected to provide a shoulder extending in the direction of the type receiving groove, and a fastening member having its ends secured to the drum for securing said type holder on the drum.

13. The combination of a rotary printing bed, adjustable means thereon including a rod for securing a printing member thereto, and a printing slug secured on said bed, said slug having an L-shaped slot therein arranged adjacent one edge thereof and adapted to fit over said rod.

14. The combination of a printing bed, a printing member thereon, said printing member having an L-shaped slot therein, and means on said printing bed for engaging one portion of the L to hold the printing member in position.

15. A printing slug having an L-shaped slot therein, leading upwardly from its base and then passing lengthwise of the slug.

16. A printing slug having an open ended slot leading upwardly from the base of the slug, the closed end of the slot being disposed at one side of the open end.

17. A type holding member in the form of a U-shaped trough provided with means for engaging type, the sides of said trough having L-shaped slots through them, one leg of the L being substantially at right angles to the base and the other leg being substantially parallel with the base.

In testimony whereof, I hereunto affix my signature.

HENRY C. OSBORN.
